UNITED STATES PATENT OFFICE.

SETH WHEELER, OF CASTLETON, NEW YORK.

DELIVERY MECHANISM FOR FOLDING-MACHINES.

No. 852,089.

Specification of Letters Patent.

Patented April 30, 1907.

Application filed March 28, 1906. Serial No. 308,398.

To all whom it may concern:

Be it known that I, SETH WHEELER, a citizen of the United States of America, and a resident of Castleton, county of Rensselaer, State of New York, have invented, certain new and useful Improvements in Delivery Mechanism for Folding-Machines and the Like, of which the following is a specification, reference being had to the accompanying drawings, forming a part thereof.

My invention relates to improvements in delivery mechanism for folding machines and the like, and particularly to means for receiving packages of folded and interfolded sheets from mechanism such as is disclosed in a co-pending application Serial No. 282,151, filed October 10th, 1905.

My invention consists, first, in the combination with a receiving box, of an improved form of resistance device therein, arranged to yieldingly resist articles as they are fed into the box, the amount of such resistance being readily adjustable, together with means whereby such resistance is caused to be uniform for the whole width of the receiving box; second, in a supplementary resistance device arranged to be brought into play when the primary resistance device is temporarily out of use, at such times for instance as when articles are being removed from the receiving box; third, in means for facilitating the removal of articles from the receiving box; and, lastly, my invention consists in certain novel details of construction and combination of parts as will hereinafter be more fully set forth.

In order that my invention may be fully understood, I will now proceed to describe mechanism in which my invention is embodied, having reference to the accompanying drawings illustrating same, and will then point out the novel features in claims.

In the drawings: Figure 1 is a top view of delivery mechanism embodying my invention. Fig. 2 is a view in transverse section through the same substantially upon the line 2-2 of Fig. 1. Fig. 3 is a detail sectional view at one end of the receiving box, showing the means for supporting a removable table. Fig. 4 is a view in side elevation of the mechanism shown in Fig. 1. Fig. 5 is a view in longitudinal section thereof substantially upon the line 5-5 of Fig. 1, but with the end portion of the receiving box shown as swung

downward out of operative position, and a removable table shown as in position, in place thereof.

For purposes of the present description, I will refer to the delivery mechanism as adapted to receive folded and interfolded sheets of paper to form interfolded packages, though it will be understood that the same is intended in no sense as a limitation on the use of the mechanism.

In Fig. 5 I have shown a small portion of a folding machine, including upper and lower folders 10, 11, which operate to fold and interfold paper units into package form; and a few of said units so folded are also illustrated at 12 in said figure. These units 12 are received in the receiving box, herein designated as a whole by the reference character 13, the rearmost sheet being engaged by a follower 14. In Figs. 1 and 4 of the drawings this follower is shown in a position at about two-thirds of the way toward the left of the receiving box, and in Fig. 5 it is shown as removed from the main portion of the box altogether (for a reason to be presently explained), but it will be understood that, in first starting up, the said follower is pushed forward to a position near the mouth of the receiving box, and is forced farther and farther back by the package as it increases in size in the box. When in such a position as shown in Figs. 1 and 4 of the drawings, the whole of the space from the mouth to the face of the follower 14 is supposed to be filled with folded and interfolded sheets comprising the package or packages.

The receiving box comprises a base 15 and sides 16. The box is open at opposite ends, as will be seen by reference to the drawings. The follower 14 is arranged to slide upon the base 15 between the sides 16, occupying the entire space widthwise between the said sides 16, and the said follower is provided with a shaft 17 journaled in bearings 18, said shaft having at its extreme ends pinions 19, which engage with longitudinal stationary racks 20 secured to the side walls 16. The engagement of the pinions 19 with the racks 20 will enforce parallel movement of the follower 14, preventing the same from assuming any position other than a position at right angles with respect to the walls of the box, and will hence enforce parallel movement of the interfolded sheets as they advance. The

follower 14 is further provided with a friction device 21 arranged centrally thereof, said friction device being in the form of a clip arranged to surround the shaft 17, and provided with means in a screw 22 for adjusting the pressure of same upon the said shaft 17. It will be understood that, as the friction device is tightened upon the shaft 17, rotation of the shaft will be resisted, and in this manner movement of the follower along the resistance box will be similarly resisted, because the said follower can only move as the shaft revolves. Adjustment of the screw 22 will then vary the resistance offered by the follower 14 to any predetermined extent, and, in this manner, just the precise amount of resistance desired to be offered to the advancing package or packages in the box may readily be produced.

The foregoing resistance means in communication with the receiving box constitutes the first part of my invention herein, and may be used, if desired, independently of the supplemental resistance means which I will now describe. This supplemental resistance means may be conveniently employed for the purpose of temporary use while a certain number of the sheets are removed from the receiving box, and until the main follower is again brought up into use. The supplemental means comprises two racks 23 arranged to travel along the upper edges of the receiving box sides 16, pinions 24 in mesh with said racks, a shaft 25 carrying said pinions, stationary bearings 26 for the said shaft, and a removable finger bar 27. The racks are arranged to move freely backward and forward by reason of their engagement with the pinions 24 when the said shaft 25 is rotated, and the said shaft may readily be rotated by means of a hand wheel 28 secured thereto at one end for such purpose. The bearings 26 are arranged as friction bearings, being adapted to grip the shaft 25 upon adjustment of the bolts 29, in the same way as the friction bearing 21 of the follower 14 is arranged, upon adjustment of the screw 22, to grip the shaft 17.

The finger bar 27 is removable, said finger bar comprising a transverse carrying member, the ends of which are arranged to be received freely in recesses 30 in the said racks 23, and dependent fingers 31 arranged to project downwardly into the receiving box in the path of the material received therein.

When it is desired to move a predetermined number of sheets from the box, the racks 23 will be moved all the way forward as far as they will go, and the finger bar will then be dropped into position with the fingers between the front sheet of the package to be removed and the rear sheet of the advancing package. The supplementary resistance means will now act to resist the onward movement of the incoming sheets, while the

primary resistance device may be pushed out of the way and the sheets contained between the primary and secondary resistance devices removed by hand. Then the primary resistance device, or follower 14, as it has been called, may be pushed up into place immediately behind the fingers 31 of the stationary device, the said finger bar 27 being then removed and the operation continued as before. It is understood, of course, that the device is normally operating with the finger bar 27 removed, and that the said finger bar is only put into position when the follower 14 is temporarily out of use. In order to guide the finger bar to its position in the recesses 30, I have provided uprising fingers 32, said fingers secured to the racks 23, and the lower portions thereof forming caps for the said recesses 30, as will be readily understood by reference to the drawings.

To further facilitate the ready removal of the sheets, and particularly the removal of a predetermined number, and to further facilitate the transporting of the removed packages from one place to another, I have constructed the end portion of the receiving box as adapted to be moved out of the way, and have provided removable tables or boxes to temporarily take the place of the part so moved out of the way, the said tables or boxes arranged to receive packages in the following manner: The end portion 43 of the receiving box 13 is shown as pivoted by means of arms 33 to the main portion, screws or bolts 34 passing through the said arms 33 into the side walls of the main portion of the receiving box, constituting the pivots therefor. Buttons 35, pivoted beneath the base 15 of the main portion of the receiving box, normally engage the movable portion 43 to hold it into position, the said portion being shown in its normal position in register with the other parts in Figs. 1 and 4 of the drawings. In Fig. 5 this movable portion is shown as swung down out of register with the main portion. In the place of this movable portion of the table in Fig. 5 there is shown a discharge table or box 36, the same comprising a bottom, sides and end portions, and a removable front wall 37. The front wall 37 is provided with pins 38, which drop into recesses in the base of the table 36 to support the said front wall in position when desired. The said front wall may be readily removed by merely withdrawing the pins from position, as by lifting the front wall 37 and pins bodily upward. The box 36 is provided with forwardly projecting slides 39 arranged to engage in guideways 40 disposed beneath the base 15 of the box 13. The box 36 may be readily placed in position and removed therefrom by merely inserting and withdrawing the said slides. This portion of my invention may be employed as follows: When the follower 14 has been pushed back to a posi-

tion clear of the main portion of the receiving box, and supported wholly by the movable end portion thereof, the said end portion may be allowed to drop down, as shown in Fig. 5, carrying the follower with it. At this time the supplementary resistance device if employed, may be conveniently brought into use by dropping the finger bar 27 into place in the recesses 30. A finger bar 42, similar to the finger bar 27, may be momentarily dropped into position at the exposed end of the receiving box 13, being supported in socket 41, this means acting to prevent the last few sheets from dropping out of the box until other means are put into position to receive them. A receiving box or table 36 may now be placed in position by inserting the slides 39 thereof into the guideways 40, but without the front wall 37. The finger bar 42 may then be removed from the socket 41, and the required number of sheets slid forward into place in the box or table 36, it being understood that the box or table 36 may be made of any desired size to accommodate the required number of sheets. During this operation, the supplemental resistance device will be operating to oppose the right amount of resistance to the fresh sheets as they enter the receiving box at the forward end thereof. After the required number of sheets have been inserted therein, the front wall 37 of the said box will be slipped into position, and the said box or table then bodily removed with its contents. The removable portion 43 of the receiving box 13 will now be swung back into position, and held in place by the buttons 35 in the manner previously stated, and the follower 14 pushed up to position again. The finger bar 27 of the supplementary resistance device will then be removed, and the part will again be in their normal operating positions.

What I claim is:

1. In a delivery mechanism, the combination with a receiving box, of a follower, a rack, a pinion, and a retarding device for the pinion.
2. In a delivery mechanism, the combination with a receiving box, of a movable follower, a rack, a pinion, an arbor for the pinion, and a friction bearing for said arbor.
3. In a delivery mechanism, the combination with a receiving box, of a movable follower, a shaft carried thereby, a friction bearing for said shaft, also carried by said follower, a pinion on said shaft, and a stationary rack for engagement with said pinion.
4. In a delivery mechanism, the combination with a receiving box, of a movable follower, a shaft carried thereby, a friction bearing for said shaft, also carried by said follower, pinions on the opposite ends of said shaft, and stationary racks with which said pinions engage.

5. In a delivery mechanism, the combination with a receiving box, of a movable follower, a shaft carried thereby, an adjustable friction bearing for said shaft, also carried by said follower, pinions on the opposite ends of said shaft, and stationary racks with which said pinions engage.

6. In a delivery mechanism, the combination with a receiving box, of main and supplemental followers, the latter arranged to be moved into and out of the path of movements of the articles delivered, at will, and adjustable resistance means for both the said followers.

7. In a delivery mechanism, the combination with a receiving box, a movable follower, and a resistance device therefor, of a supplementary removable follower, means for supporting the said follower in the path of movement of articles to be delivered, and a resistance device for the said supplementary removable follower.

8. A delivery mechanism comprising a receiving box having a part adapted to be moved out of register with the remaining portion of the box, said part forming normally a continuation of the said box, and a follower arranged to move from one part of said box to the other, and to be carried by said movable part of said box when the same is moved out of such register.

9. In a delivery mechanism, the combination with a receiving box comprising a main portion and an extension, of a movable follower arranged to move along said box and into said extension, a resistance device for the movable follower, and means for moving said extension and said follower out of register with the main portion of said receiving box.

10. In a delivery mechanism, the combination with a receiving box having a part thereof pivoted to the main portion, and means for normally maintaining the extension in register with the main portion, of a follower arranged to move along said receiving box into said extension, and resistance means for said follower operating during the movement of said follower both in the main portion of said box and in the extension thereof.

11. In a delivery mechanism, the combination with a receiving box having a movable portion, and a follower arranged to move along said box into said movable portion, of a supplemental follower, and resistance means for both main and supplemental followers.

12. A delivery mechanism comprising a receiving box having a movable extension forming normally a continuing part of said box, and a removable table adapted to be substituted at will for said movable extension.

13. A delivery mechanism comprising a receiving box having a movable extension forming normally a continuing part of said box, a follower arranged to travel along said box and into the extension thereof, and a removable table adapted to be substituted at will for said movable extension.

In witness whereof I have hereunto set my hand in the presence of two witnesses.

SETH WHEELER.
